UNITED STATES PATENT OFFICE.

LOUIS V. ARONSON, OF NEWARK, NEW JERSEY.

TOY PISTOL.

Application filed March 20, 1922. Serial No. 543,049.

To all whom it may concern:

Be it known that I, LOUIS V. ARONSON, a citizen of the United States, residing at Newark, in the county of Essex and State 5 of New Jersey, have invented certain new and useful Improvements in Toy Pistols, of which the following is a specification.

The invention relates to toys and has for an object the provision of a toy in the form 10 of a pistol, which when actuated will produce sparks giving somewhat the appearance of a real pistol and which may be actuated many times in succession without reloading.

15 An illustrative embodiment of the invention is shown in the accompanying drawings, in which—

Figure 1 is a side elevation with a portion of the casing removed;

20 Figure 2 is a vertical section on line 2—2 of Figure 1; and

Figure 3 is a detail exploded view of some of the parts.

The casing 10 of the toy is made to resemble 25 an automatic revolver. The two halves thereof may be secured together by means of struck-up tongues coacting with struck-up lugs 11. The entire mechanism of the pistol is preferably mounted upon a 30 plate 12, which may be secured to one-half of the casing as by means of tongues 13 integral with the plate projecting through openings in the casing and clinched as shown in Figure 2.

35 To guide an actuating bar 14 in its movement, a lug 15 is bent out at an angle from the plate 12 and is provided with an opening 16 through which the plate 14 may pass and in addition a wing portion 17 is struck 40 out from the material of the plate 12 at an angle thereto. The action of the toy is due to friction caused upon a piece of pyrophoric metal causing a shower of sparks to be projected therefrom. To provide the 45 friction mentioned, a friction wheel 18 having teeth 19, of the nature of file teeth on the edge thereof is pivoted upon a pin which may be mounted in an opening 20 in the plate 12. To provide movement of the wheel 50 18, a lever 21 having a wheel portion provided with ratchet teeth 23 upon its periphery, is secured to the wheel 18, the wheel portion 22 being concentric therewith. The end of the lever 21 is shown 55 as notched at 24 and attached to a coiled spring 25 which spring causes sudden re-

turn to normal of wheel 18 when released as will be described.

To cause movement of the wheel 18 the 60 sliding plate 14 is provided with a series of pawl teeth 26, which when the plate 14 is reciprocated coact with the ratchet teeth 23 and revolves the wheel 18 with stressing of the spring 25. The spring 25 is moreover anchored to the trigger 27 which is provided 65 with a lug 28 for the purpose and when the plate 14 is moved to the rear by pressure upon the trigger 27, the spring 25 will be tensioned by a pull upon its ends in both directions. When movement of the plate 70 14 to the rear has caused all of the pawl teeth 26 to be moved out of range of the ratchet teeth 23 and the smooth portion 29 of the plate 14 impinges upon the ratchet teeth 23, the wheel 18 will be suddenly released and the spring 25 being stretched to 75 its maximum extent will suddenly and sharply return the wheel 18 to normal position providing friction upon the pyrophoric element and a resultant shower of 80 sparks.

The trigger 27 is shown as rigidly secured to the plate 14 at two points by means of tongues 30, 31 which are bent about portions of the trigger where it intersects the 85 plate 14. A stop pin 32 is shown projecting from the plate 12 to limit the rearward movement of the lever 21.

To hold a pyrophoric element a loop 33 is shown upon the end of a tongue 34 struck 90 out from the plate 12. To provide pressure upon the element mounted in the loop 33, with resultant friction of the element upon the wheel 18, a projection 35 is shown mounted upon a member 36 pivoted at 37 upon the plate 12, the pivot being shown as being actually upon a portion of the tongue 34, which is provided with an opening 38 for reception of the pivot pin. The member 36 is shown as provided with a projecting thumb piece 39 for retraction of projection 35 when it is desired to insert a fresh pyrophoric element. To provide the pressure upon the element a portion of the member 36 is shown as projecting below the pivot at 40 to which 95 projection a spring 41 is anchored, its other extremity being anchored to a lug 42 shown as integral with the trigger 27 but which might equally well be formed upon the plate 14. As the plate 14 is moved to the rear the tension upon the spring 41 increases and is 100 at its maximum during the entire spark pro-

ducing action of the wheel 18. By this arrangement the friction upon the pyrophoric element is slight during the initial movement to the rear of the plate 14, thereby avoiding a considerable portion of unnecessary wear upon the pyrophoric element.

The operation of the device will be clear from the above description, and minor changes may be made in the physical embodiment of the invention without departing from the spirit.

I claim:

1. A toy pistol comprising a casing, a friction wheel mounted in said casing, a spring resisting a movement in one direction of said wheel, a reciprocating plate mounted in said casing, ratchet teeth carried by said wheel, pawl teeth carried by said plate, said plate having a smooth portion beyond said pawl teeth, whereby movement of said plate will cause movement of said friction wheel against resistance of said spring until the smooth portion comes in contact with the ratchet teeth when the friction wheel will be suddenly returned to normal, and a pyrophoric element in contact with said wheel.

2. A toy pistol comprising a casing, a friction wheel mounted in said casing, a spring resisting a movement in one direction of said wheel, a reciprocating plate mounted in said casing, ratchet teeth carried by said wheel, pawl teeth carried by said plate, said plate having a smooth portion beyond said pawl teeth, whereby movement of said plate will cause movement of said friction wheel against resistance of said spring until the smooth portion comes in contact with the ratchet teeth when the friction wheel will be suddenly returned to normal, a trigger rigidly secured to said plate, and a pyrophoric element in contact with said wheel.

3. A toy pistol comprising a casing, a friction wheel mounted in said casing, a lever projecting from said wheel, a

plate slidably mounted in said casing, means carried by said plate to cause revolution of said wheel and sudden release thereof, a spring anchored upon said lever at one end and upon said sliding plate at its other end whereby movement of the plate will separate the anchors of said spring to increase the tension thereof and a pyrophoric element in contact with the said wheel.

4. A toy pistol, comprising a casing, a friction wheel mounted in the casing, a pyrophoric element in contact with said wheel, a plate slidably mounted in said casing for actuation of said wheel from normal, a member pivoted in the casing having a portion adapted to press upon said element, a spring so anchored to said member as to cause such pressure, the opposite end of the spring so anchored to said sliding plate that movement of the wheel from normal will be accompanied by an increase of pressure upon said pyrophoric element.

5. A toy pistol, comprising a casing, a plate mounted in the casing, a friction wheel provided upon the plate, a lever rigidly secured to said wheel, a stop for limiting the movement of said lever in one direction, a reciprocating plate slidably mounted upon said first named plate having pawl teeth thereon and a smooth extension beyond said teeth, ratchet teeth carried by said wheel co-acting with said pawl teeth, a trigger rigidly secured to said reciprocal plate, a spring anchored to said lever and to said trigger whereby movement to the rear of said reciprocal plate will cause movement from normal of said wheel and sudden release when said pawl teeth pass beyond said ratchet teeth and whereby the spring will suddenly return the friction wheel to normal and will also return the reciprocal plate to normal when pressure upon the trigger is released.

LOUIS V. ARONSON.
